UNITED STATES PATENT OFFICE

158,841

FOLDING CHAIR

Roger G. Cudini, Birmingham, Mich., assignor to
Moynahan Bronze Company, Detroit, Mich., a
corporation of Michigan

Application June 23, 1949, Serial No. 3,461

Term of patent 14 years

(Cl. D15—1)

To all whom it may concern:

Be it known that I, Roger G. Cudini, a citizen of the United States of America, residing in the city of Birmingham, county of Oakland, State of Michigan, have invented a new, original, and ornamental Design for a Folding Chair, of which the following is a specification, reference being had to the accompanying drawing, forming a part thereof.

Figure 1 is a front and side perspective view of a folding chair showing my new design; and

Fig. 2 is a rear and side perspective view thereof.

I claim:

The ornamental design for a folding chair, as shown.

ROGER G. CUDINI.
